UNITED STATES PATENT OFFICE.

NAPOLEON CHOQUETTE, OF ST. LUDGER, QUEBEC, CANADA.

BUTTER-FORMING MACHINE.

1,207,865.

Specification of Letters Patent. Patented Dec. 12, 1916.

Application filed April 24, 1915. Serial No. 23,642.

To all whom it may concern:

Be it known that I, NAPOLEON CHOQUETTE, a subject of the King of Great Britain, residing at St. Ludger, Frontenac county, Province of Quebec, Canada, have invented certain new and useful Improvements in Butter-Forming Machines; and I do hereby declare that the following is a full, clear, and exact description of the invention, such as will enable others skilled in the art to which it appertains to make and use the same.

My invention refers to machine for use in butter making-dairies and more particularly, it is a machine for forming the worked butter into equal pieces of a pound or any other usual standard-measure.

For obtaining that purpose my invention consists of parts, which in the running of the machine, automatically cut a layer of butter of equal thickness into strips and cut the strips into single pieces, transporting the butter from the one side of the machine to the other side, so that continually butter can be fed at the one side and the cut pieces can be taken away at the other side of the machine.

Other details of the invention will be made clear in the following description.

In order to more clearly disclose the construction, operation, and use of the invention, reference should be had to the accompanying drawings forming part of the present application.

Throughout the several figures of the drawings like reference characters designate the same parts.

In the drawings: Figure 1 is a side elevation of the new machine, partly in section; Fig. 2 is a plan view of same; Fig. 3 is a side elevation of the part of the machine for transporting the cut strips of butter to the mechanism, which cuts the strips into pieces; Fig. 4 is a perspective view of the cutter which cuts the layer of butter to strips; Fig. 5 is a detail of the driving mechanism of the cutter; and Fig. 6 is the table for rolling the butter to a layer.

In the shown embodiment of my invention the butter, after having been worked in the churn and on a table-plate, a butter-worker or a working-annex to the churn, is put on the table shown in Fig. 6, which consists of a wheel-mounted lower-frame 1,

legs or supports 2 and trusses 3 on the front end and the upper-frame 4 with handles 5. The table according to Fig. 6 has trusses 3 and no legs at its rear end; because its use in combination with some kinds of churns and with the special construction of my butter-cutting device to be described make such construction preferable; but likewise any other constructions may be used. On the upper frame 4 a plate 6 with two lateral borders 7 is put, and by means of a roller 8 rolling on the two borders 7 the heap of butter which is put on the plate 6, can be rolled into a layer of equal thickness.

The butter cutting machine comprises a support as better shown in Figs. 1 and 2 consisting of a plurality of vertical spaced legs 9 some of which are connected by the cross bars 9'. Supported upon these legs and extending transversely thereof are the transverse bars 10. Also mounted upon the bars 9 is an extended frame comprising vertically extending boards 27 and horizontally arranged bars 27'. Journaled within bearings 11 supported upon the horizontal bars 27' is a driving shaft 11 which can be driven by any suitable source of power. Keyed upon the shaft 11 adjacent each end thereof are disks 12 the purpose of which will be later described and connected to the opposite ends of the shaft are gear wheels and in the drawing only one of these gear wheels 13 is shown.

In Fig. 2 of the drawings I have illustrated one side of the butter cutting machine but of course the other side of the machine is to be a duplicate thereof and for this reason it is thought that further explanation or showing of the machine is deemed unnecessary.

Journaled in suitable bearings carried by the frame are the gear wheels 14 and 15 which are in mesh with each other and the gear wheel 14 being in mesh with the gear 13. Journaled within a bearing carried by the bar 10 is a shaft 16 having keyed to the outer end thereof a bevel gear adapted to mesh with the bevel gear 17 carried by the shaft 18 and the latter may be supported in suitable bearings carried by the bar 10. Carried by the shaft 18 are bevel gears 19 which are adapted to mesh with bevel gears carried by the shafts 20 and journaled within the bearings 20' supported upon the bar 10.

The inner ends of these shafts 20 are journaled within the boards 27 having keyed thereto the sprocket wheels 24.

Adjustably mounted within the frame of the machine are a plurality of horizontally arranged bars 21 and 22 which have rigidly connected thereto the cutting blades or knives 23. These knives 23 extend parallel with each other and are adapted for reciprocating movement whereby they will cut the butter into blocks of the proper configuration.

Secured upon the boards 27 are the idler sprocket wheels 26 over which passes the sprocket chain 25 and the latter is adapted to mesh with the sprocket wheel 24. Two of these sprocket chains are arranged at each side of the frame of the machine and each carry an apertured projection 28 in which are adapted to rest the outer ends of the rods 29. These rods 29 are slidably mounted within the boards 21 and 22 and the inner ends of each pair of alining rods are connected by the tonguelike shifting arms 30 which serve as a means of adjusting the arms so that the rods 29 may be inserted within the openings 28 of the lugs carried by the chains 25. These shifting arms 30 may be manually adjusted for also releasing the arms 29 from their connections so that the sprocket wheels 24 may continue with their rotation but the knives may be thrown out of use.

Journalized upon the bars 27' is a shaft 35 having a crank handle 31 at each end thereof whereby the same may be manually rotated and connected to this shaft are the chains 32 having their opposite ends connected to the rods 29 whereby when said rods 29 are released from the sprocket chains 25 and the crank handles rotated the knives 23 and their supporting frame may be raised and lowered. The butter properly rolled out upon the table 6 is now in form to be cut by the cutting knives 23 and by removing the roller 8 and inserting the table into the butter cutting machine as better illustrated in Fig. 1 the butter is then placed in position to be cut into blocks of the desired dimensions. The knives 23 and the frame to which they are connected may be lowered by releasing the crank handles 31 and the rods 29 brought into locking engagement with the lugs 28. Upon the rotation of the shafts 20 the sprocket chains 25 will be caused to travel through their rectangular planes carrying the butter cutting blades therewith whereby upon the downward movement of the cutting blades they will be pressed into the layer of butter on the plate 6 and cut the same into equal strips. Upon the further movement of the sprocket chains 25 along the lower horizontal plane in which the chains travel the cutting knives will be moved horizontally over the board 6 pushing

the blocks of butter indicated by the letter A across the board and upon the further traveling of the sprocket chains in a vertical plane the cutting knives will be raised out of contact with the butter and again directed back to the position for cutting the next layer of butter contained upon the table 6.

Pivottally connected as at 34 to the side of the supporting frame are levers 33 only one being shown in the drawing having slidably mounted upon one arm thereof an L shaped receiving tray 135 which is adapted to receive each block of butter A as it is forced from the table 6 by means of the knives 23. The opposite end of this lever 33 extends upwardly as at 34 and is adapted to lie in the path of travel of a cam projection 35 carried by the disk 12 so that when the cam 35 strikes the arm 34 it will raise the lever 33 and bring the L shaped receiving tray 135 upwardly and into the path of travel of a casting 36 supported at each end upon the disk 12. This casting 36 is divided up into a plurality of chambers so that when each bar of butter A is delivered thereto the same will be cut transversely into a plurality of blocks preferably weighing a pound each. The outer ends of the levers 33 are cut away upon which is adapted to slide the tray 35 and thereby leave a shoulder projection 33. Pivottally mounted upon the trays 135 is a bell crank lever 42 having one end thereof adapted to rest against the shoulder 43 for holding the trays 135 adjacent to the table 6 and preventing the trays from sliding upon the levers while the bars of butter are being delivered thereto. When the lever 33 is swung upon its pivot connection 134 and the disk 12 rotated the lug projection 40 carried by the casting 36 will strike against the hook 41 carried by the tray 135 which in turn will cause the lever 42 to swing upon its pivot and be released from the shoulder 45 thereby permitting the tray 135 when in its raised position to slide upon the arms 33 or assume the position as better shown in Fig. 1 so that the casting 36 will receive the full block of butter carried by the tray. Upon the return movement of the lever 33 the tray 135 will ride upon the cam projection 41' where it will be forced to the outer ends of the lever 33 and again locked in position by means of the lever 42. To cause the lever 33 to return to its normal position a lateral projection 44 is carried by the cam 35 and is adapted to contact with the pivoted lever 45 which rests upon the arm 34 of the lever 33 whereby upon the rotation of the disk 12 the cam 35 will first raise the lever 33 but when the lug 44 strikes the lever 45 it will press against the arm 34 and return the lever 33 to its normal position.

Slidably mounted within each compart-

ment of the casting 36 is a plunger 37 and extending from each plunger is a rod 38 and rigidly connecting each of the rods 38 is a bar 39. When the casting 36 comes adjacent 5 to the supporting tray 47 carried by the support 46 the plungers will be brought into operation for forcing the butter from the compartments contained within the casting whereby the blocks of butter will be delivered 10 to the tray 47 and this tray may be covered with paraffin paper or the like whereby each block of butter may be properly wrapped. To cause these plungers 37 to be brought into operation a lever 49 is pivotally mounted as at 50 to the disk 12 and the outer end of this lever is adapted to contact with the bar 39. Projecting from the support 10 is a bar 48 which is adapted to extend within the travel of the lever 49 so that when the lever 49 contacts with the bar 48 it will be caused to swing upon its pivot and in turn the bar 39 will be moved. The projection 48 is a resilient blade and to release the same from the lever 25 49 a cam projection 51 is also carried by the disk 12 so as to engage under the bar 48 and force the same away from the disk where it will be caused to release the lever 49. Also pivotally mounted upon the frame 30 10 is a spring pressed pawl 52 which is adapted to extend in the travel of the outer free end of the lever 49 so as to engage the outer end of this lever after the bar 48 has been released from the lever so as to cause 35 the plungers 37 to return within the compartments within the casting 36 so that they may receive a new supply of butter.

It is thought that the construction, operation, and use of the invention will be clear 40 from the preceding detailed description.

Changes may be made in the construction, arrangement, and disposition of the several parts of the invention, without in any way departing from the field and scope 45 of the same, and it is meant to include all such within this application wherein only a preferred form has been disclosed.

Having thus fully described my invention, what I claim as new and desire to secure 50 by Letters Patent is:

1. In a butter-forming machine, a device

for cutting a uniform layer of butter into equal strips, consisting of, a number of parallel knives at equal distance from each other and fixed at bars which are crossing 55 the knives; endless chains at the side of the front-end and at the rear-end of the knives, adapted to move in a rectangular way in vertical planes at right angles to the knives; means for connecting the knife-bearing 60 cross-bars to the chains, so as to impart to the cross-bars and to the knives a movement in a rectangular vertical way; means for disconnecting the cross-bars and knives from the chains if desired, and for raising 65 and keeping the cross-bars and knives in the raised position.

2. In a butter-forming machine, a device for cutting equal strips of butter into equal pieces of pound-size or any other standard 70 market-size, consisting of a square or mold, adapted to receive the strip of butter from a foregoing part of the machine; a casing of the size of the strips of butter and divided by partitions into chambers of the 75 pound-size or other desired market-size; a swinging lever, bearing at its one end the butter-strip-bearing square or mold and adapted to swing it into the way of the chambers-containing casing for transferring 80 the butter from the square or mold to the chambers, and to swing it back after that to its first position for receiving a new strip of butter; a plate or mold on the side of the machine with compartments adapted 85 to receive the pieces of butter contained in the aforementioned chambers; pistons on the bottom of the chambers, adapted to press the pieces of butter out of the chambers and on the aforementioned compartments; means 90 for swinging to and fro the aforementioned lever; and means for moving the chambers containing casing and the pistons in the casings, so as to receive respectively to press out the butter, substantially as described and 95 illustrated.

In witness whereof I have hereunto set my hand in the presence of two witnesses.

NAPOLEON CHOQUETTE.
